UNITED STATES PATENT OFFICE.

PAUL RUSSELL CUMMING, OF CHICAGO, ILLINOIS, ASSIGNOR TO THE HANDY THINGS COMPANY, OF SAME PLACE.

DESIGN FOR A BLOCK FOR SCRUBBING-BRUSHES AND DRIERS.

SPECIFICATION forming part of Design No. 32,171, dated January 30, 1900.

Application filed October 27, 1899. Serial No. 734,994. Term of patent 7 years.

To all whom it may concern:

Be it known that I, PAUL RUSSELL CUMMING, a citizen of the United States, residing at Chicago, in the county of Cook and State 5 of Illinois, have invented a certain new and useful Design for Blocks for Scrubbing-Brushes and Driers, of which the following is a specification.

My design is illustrated in the accompanying drawings, in which—

Figure 1 represents a perspective view of a block for a scrubbing-brush and drier embodying my invention, and Fig. 2 is an end elevation thereof.

15 The leading feature of my design consists of a generally oblong block having in end elevation the shape of an irregular pentagon, two opposite sides of which have curved portions and one face of which has a rectangular 20 notch therein and stands at a right angle to one of the sides and at an oblique angle to the other sides.

Referring now to the drawings and with reference to the position of the block as it is 25 illustrated, the block consists of the body portion A, having squared parallel ends and five sides extending between the five sides connecting said ends. The lower side B in the position of the block shown in the drawings 30 is horizontal. The upper side C is oblique to

the lower side and somewhat longer than said side, while the front side D is vertical and merges into the upper side on a curved line. There are two other sides which together make up the rear side of the block, one of them, E, 35 extending substantially at right angles to the oblique side C and the other side, F, having one straight portion substantially parallel with the side C and another straight portion substantially parallel with the front side D, 40 said straight portions being connected by a curved portion of a length about equal to each of the straight portions. The side E is given a bifurcated appearance by having the rectangular groove G formed therein throughout 45 its length.

The oblong block with the irregular pentagonal shape in cross-section shown in the drawings gives to the block a characteristic and distinguishing appearance. 50

Having thus fully described my invention, what I claim, and desire to secure by Letters Patent, is—

The design for a block for a scrubbing-brush and drier, substantially as herein shown and 55 described.

PAUL RUSSELL CUMMING.
